VARIABLE CHANGE SPEED HOIST

Trevor O. Davidson, Milwaukee, Wis., assignor to
 Bucyrus-Erie Company, South Milwaukee, Wis.,
 a corporation of Delaware

Application March 12, 1941, Serial No. 382,923

6 Claims. (Cl. 214—135)

My invention relates to new and useful improvements in hoists, more particularly to the hoisting mechanism of excavators of the type having a boom and an outward digging dipper mounted on the end of a handle, which handle is reciprocable with respect to a point on the boom known as the shipper shaft, the dipper being movable in a circle about this point as a center.

The hoisting line usually extends from a winding drum on the main frame of the excavator, over a sheave on the outer end of the boom, to the dipper and handle, and thence over another sheave on the boom to an anchorage on the boom.

Frequently it is desirable that the operator of such an excavator be able to change the speed of hoisting the dipper, and be able to make this change of speed at selected points of the hoisting cycle. Thus when the dipper is digging, it is desirable to move it at low speed with high applied force; and when the dipper is hoisting, or is doing light digging, it is advantageous to move the dipper at high speed with lower applied force. Furthermore, since digging conditions differ on each job, the point in the hoisting cycle at which the speed is changed should be variable, but once the point has been determined for any given job, the change of speed should thereafter be automatic throughout that job. Lastly, the means for accomplishing the change of speed and for varying the point of change speed should be simple and inexpensive.

Accordingly it is the principal object of my invention to provide, for control of the hoisting line, the novel combination of a multiple-diameter winding drum and a variable anchorage, whereby the hoisting speed may be changed automatically, and the point of change speed may be varied.

Another object resides in the provision of means for varying the point of change speed, which means is independent of the means for changing hoisting speed, and is simple to construct and to operate.

In addition to my principal objects, I have worked out a number of novel and useful details, which will be readily evident as the description progresses.

My invention consists in the novel parts, and in the combinations and arrangements thereof, which are defined in the appended claims; and of which two embodiments are exemplified in the accompanying drawing, which is hereinafter particularly described and explained.

Throughout the description, the same reference

number is applied to the same member or to similar members.

Referring to the accompanying drawing, it will be seen that:

5. Figure 1 is a conventionalized side elevation of an excavator equipped with my invention, showing the dipper in two positions. In the digging position, the dipper and the hoisting-line are shown by full lines; in the hoisting position, they are shown by dotted lines.

Figure 2 is a rear elevation of a two-diameter drum, taken along the lines 2—2 in Figure 1. This is one embodiment of a part of my invention.

15 Figure 3 is a similar rear elevation of a tapered drum, which is another embodiment of the same part of my invention.

Referring now more particularly to Figure 1, we see that I have illustrated an excavator or power shovel of a conventional type, omitting, 20 however, certain details as not essential to an understanding of the invention. Well known details of this type of excavator are: the main base 11 which is ordinarily revolvable on a propelling traction mounted base (not shown); an upwardly 25 inclined boom 12 pivoted at its foot to the base 11; a suspension (not shown) for the boom; a dipper handle 13, carrying at its outer end a dipper 14; and a power driven shipper shaft 15 journalled on the boom for effecting reciprocation of 30 the dipper handle. The method of driving this shipper shaft is immaterial to the present invention. Thus it may be driven by an engine 16 located adjacent to it (as shown in Figure 1), or by any other conventional expedient. A hoisting 35 winch or drum 17, driven by an adjacent engine 18, is shown mounted on the base, although it may be mounted on any other part of the machine which in turn is supported by the base. A hoisting line 19, anchored and wrapped upon this 40 hoisting-drum, is trained over one of the sheaves 20 at the outer end of the boom, to a sheave 21 on the dipper, and thence over another sheave 20 to an anchor 22 on the boom. The hoisting line may consist of a rope, chain, or other flexible tension member.

A principal element of my novel hoisting mechanism is the multiple-diameter hoisting drum 17, two embodiments of which are shown in Figures 2 and 3. In Figure 3 the barrel of the drum is 45 tapered and provided with a continuous groove 23 for guiding the hoisting-line from the small to the large end of the drum and vice versa. In Figure 2 the drum is formed with two portions 24 and 25 of different diameters. The groove 26 at the large end 24 of the drum is connected with

the groove 27 at the small end 25 thereof by a transitional groove 28. In both types of drum the hoisting-line 19 is anchored at 33 on the small low speed end 25 of the drum and is wound on the drum up over the large end 24. The direction of winding depends on the direction in which the groove is cut. For example, in Figures 2 and 3 the grooves are shown running clockwise from the small to the large end (considering the drum as viewed from the right as in Figure 1). Winding the hoisting-line up on the drum effects a change from low-speed high applied force to high-speed low applied force. If the drum illustrated in Figure 2 is employed, this change occurs suddenly at a point in the hoisting cycle which is determined by the adjustment of the variable anchorage which is the second important element of my invention.

In Figure 1 one form of variable anchorage is shown on the upper part of the boom. The illustrated form of anchorage consists of a plate 29 mounted lengthwise on the boom and perforated with longitudinally spaced holes 30 for receiving a removable pin or bolt 31 to which the hoisting-line 19 is dead ended. It is understood, however, that my invention is not limited to this particular form of variable anchorage, but covers any adjustable or operable device, preferably independent of the hoisting means, whereby the working portion of the hoisting-line may be shortened or lengthened. Changing the point of anchorage, by inserting the anchorage pin or bolt in another hole, or by adjusting or operating any other form of variable anchorage device, effects a change in the point of change speed in the hoisting cycle, and also shifts the point of rope wear.

In Figure 1 full lines show the dipper in digging position, with the hoisting line on the low speed small diameter portion of the drum; and dotted lines show the dipper in hoisting position, with the hoisting line on the high speed large diameter portion of the drum. If digging is light, the dipper may be operated at high speed in both the digging and hoisting positions by dead-ending the hoisting-line at the outer anchorage 32, since the point of change speed will then be at the lowest extreme of the hoisting cycle, and only line wound on the large diameter portion 24 of the drum will be active. Conversely, if the digging is heavy, the dipper may be operated at low speed in both the digging and hoisting positions by dead-ending the hoisting-line at the inner anchorage, so that only line wound on the small diameter portion 25 of the drum will be active.

Having now described and illustrated one form of my invention, I wish it to be understood that my invention is not to be limited to the specific form or arrangement of parts herein described and shown, except as specifically covered by my claims.

I claim:

1. In a power shovel, the combination of: a boom; guide sheaves on the boom; a dipper handle; a dipper carried by the handle; means for reciprocating the dipper handle; a multiple diameter hoisting drum formed with a continuous cable-guiding groove; and a hoist rope having a live end and a dead end, its live end being attached to and wrapped upon the hoisting drum, trained over the guide sheaves, and connected with the dipper, and its dead end being attached

to an anchor selectively positionable in a number of positions, to vary what diameter of the drum is effective in different portions of the hoisting cycle, by means including adjustable pin connection means mounted along the length of said boom for anchoring the hoist rope at any one of a plurality of longitudinally spaced points along said boom.

2. In a power shovel, having: a boom, a dipper handle, and a dipper carried by the handle, the combination therewith of: a flexible hoist member having a live end and a dead end; a winch capable, at a constant speed, of imparting variable speed to the live end of said hoist member, dependent on the degree of travel thereof; and, independent of such winch, an anchor for the dead end of said hoist member, said anchor being selectively positionable in a number of positions to vary what degree of travel occurs in different portions of the hoisting cycle.

3. In a hoist, the combination of: a load handling means; a flexible hoist member having a live end and a dead end; a multiple diameter hoisting drum for imparting variable speed to the live end of said hoist member; and an anchor for the dead end of said hoist member, said anchor being selectively positionable in a number of positions to vary what diameter of the drum is effective in different portions of the hoisting cycle.

4. In a power shovel, the combination of: a boom; guide sheaves on the boom; a dipper handle; a dipper carried by the handle; means for reciprocating the dipper handle; a multiple diameter hoisting drum formed with a continuous cable-guiding groove; and a hoist rope having a live end and a dead end, its live end being attached to the small diameter end of said drum and wrapped upon the small and large diameter portions of said hoisting drum, trained over the guide sheaves, and connected with the dipper, and its dead end being attached to adjustable pin connection means mounted along the length of said boom for anchoring the hoist rope at any one of a plurality of longitudinally spaced points along said boom.

5. In a power shovel, the combination of: a boom; guide sheaves on the boom; a dipper handle; a dipper carried by the handle; means for reciprocating the dipper handle; a multiple diameter hoisting drum; and a flexible hoist member having a live end and a dead end, its live end being attached to and wrapped upon the hoisting drum, trained over the guide sheaves, and connected with the dipper, and its dead end being attached to adjustable pin connection means mounted along the length of said boom for anchoring the flexible hoist member at any one of a plurality of longitudinally spaced points along said boom.

6. In a hoist, the combination of: load handling means; a flexible hoist member having a live end and a dead end; a multiple diameter hoisting drum for imparting variable speed to the live end of said hoist member; and an anchor for one end of said hoist member, said anchor including adjustable pin connection means for anchoring said hoist member at any one of a plurality of spaced points.
